[57] CLAIM

The ornamental design for a kiosk, as shown and described.

DESCRIPTION

FIG. 1 is a perspective view of a kiosk embodying the present invention;

FIG. 2 is a reduced side elevational view of the kiosk illustrated in FIG. 1;

FIG. 3 is a front elevational view of the kiosk illustrated in FIG. 2;

FIG. 4 is a rear elevational view of the kiosk illustrated in FIG. 2;

FIG. 5 is an opposite side elevational view of the kiosk illustrated in FIG. 2;

FIG. 6 is a top plan view of the kiosk illustrated in FIG. 2; and,

FIG. 7 is a perspective view of a second embodiment of the kiosk as disclosed in FIG. 1.

The undisclosed sides of the second embodiment are identical to those disclosed in the first embodiment.
